Primary Examiner — Andrew Kerr*Assistant Examiner* — Caitlin A Laverty(57) **CLAIM**

I claim the ornamental design for a dog-walking supply waist pouch, as shown and described.

DESCRIPTION

FIG. 1 is a front view of the dog-walking supply waist pouch, showing my new design.

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The dog-walking supply waist pouch is shown with symbolic breaks in its length.

The appearance of any portion of the article between the break lines forms no part of the claimed design.

The short broken lines represent stitching that form no part of the claimed design. The long broken lines represent portions of an article that form no part of the claimed design.
